SOUND TUBE FOR TALKING MACHINES

Original Filed June 23, 1921

Fig. 1.

Patented July 7, 1925.

1,544,589

UNITED STATES PATENT OFFICE.

WILLIAM W. MOYER, OF COLLINGSWOOD, NEW JERSEY, ASSIGNOR TO VICTOR TALKING MACHINE COMPANY, A CORPORATION OF NEW JERSEY.

SOUND TUBE FOR TALKING MACHINES.

Application filed June 23, 1921, Serial No. 479,733. Renewed November 17, 1924.

To all whom it may concern:

Be it known that I, WILLIAM W. MOYER, a citizen of the United States, and a resident of Collingswood, in the county of Camden and State of New Jersey, have invented certain new and useful Improvements in Sound Tubes for Talking Machines, of which the following is a specification.

My invention relates to certain improvements in talking machines, and more particularly to sound-tubes or sound conduits, comprising the tone arm proper, the gooseneck or other tube to which the sound box may be attached, and the connection between the tone arm and the gooseneck by means of which a continuous passage for sound waves is provided between the sound box and any suitable amplifier with which the tone arm may be in communication, and the sound box is free to oscillate vertically in its travel across the face of the record, and the sound box may be swung upwardly away from the record.

The objects of my invention are to provide a sound conduit or sound conveying tube in which there is a substantially continuous tapering passage from the sound box to the amplifier, with which the larger end of the tone arm is in communication; in which there are few parts which are readily and easily assembled; in which the gooseneck is free to rotate smoothly in the end of the tone arm proper without frictional resistance to such motion but without any looseness between the gooseneck and the tone arm; wherein any wear in the bearings between the gooseneck and the tone arm may be readily taken up; in which any rattle or vibration between the gooseneck and the tone arm is absolutely eliminated; and in which the assembled tone arm and gooseneck present an attractive appearance.

Other objects of my invention will appear in the specification and claims below.

In the drawings forming a part of this specification and in which the same reference characters are employed in the various views to designate the same parts, Fig. 1 is a side elevational view of my improved sound conveying tube with the relative positions of the sound box, turntable spindle and the motor board indicated in dot and dash lines.

Fig. 2 is a plan view, partly in section, of the end of the tone arm, the gooseneck, and the connection therebetween, with the posi-

tion of the sound box indicated in dot and dash lines.

In Fig. 1 is shown a portion 1 of a cabinet of a talking machine, which portion may be the top of a cabinet, or a partition within a cabinet. To the under side of the motor board 2, a motor (not shown) may be secured in the usual manner, said motor being arranged to rotate the vertical spindle 3, on the upper end of which the turntable 4 is mounted to support and rotate a sound record 5. The sound-box 6 may be secured by the bayonet joint 7 and pin 8, to the free end of the gooseneck 9, and it is of course provided with the usual stylus 10 arranged to track in the grooves in the face of the sound record.

The larger end of the tone arm 11 has a bearing in the bracket 13, and a coaxial bearing 14 in the overhanging end 15 of the bracket 13, and upon these bearings, 12 and 14, the tone arm 11 is free to swing upon a vertical axis in a plane parallel to the face of the sound record 5. It is to be understood that the larger end of the tone arm 11 might be directed upwardly instead of downwardly to communicate with an amplifier above the tone arm, a suitable bracket being obviously necessary for so mounting the tone arm.

When the stylus 10 is in engagement with the groove in the record 5 and the record is rotated, the tone arm 11 and gooseneck 9 swing in a horizontal plane about the axis of the bearings 12 and 14 and the reproduced sound is transmitted through the gooseneck 9 and tone arm 11 to the amplifier.

The smaller free end 16 of the tone arm 11 is provided with a relatively short transverse cylindrical sleeve 17, one end 18 of which is closed except for a small beveled hole 19 therein at the center thereof, and the other end of which is open, the said open end being provided with an inwardly converging narrow beveled or conical bearing 20. The sleeve 17 is permanently and rigidly secured to the small end 16 of the tone arm 11 in any substantial manner as for instance by brazing or soldering.

The gooseneck 9 is, generally speaking, tapered throughout its length. The ends, however, may be and preferably are cylindrical. The smaller end 21 of the gooseneck is adapted to fit into the opening in the back of a sound box 6, and is secured there-

to by a pin 8 on the sound box sliding into a bayonet slot 7 in the end of the gooseneck 9.

The larger end 22 of the gooseneck 9 is preferably cylindrical and may be closed by a plug 23 rigidly secured thereto, as for instance, by brazing or soldering. Between the cylindrical end 22 and the tapered portion of the gooseneck or sound box tube 9 is a shoulder 24 providing a narrow conical surface 25 adapted to fit smoothly against the conical surface 20 of the sleeve 17.

The plug 23 is provided with a screw threaded opening 26 arranged coaxially with respect to the cylindrical end 22 of the gooseneck and adapted to receive a split screw 27, the head 28 of which is preferably conical and adapted to fit within the beveled opening 19 in the closed end 18 of the sleeve 17. The end 22 of the gooseneck 9, and which is within the sleeve 17, is of a diameter substantially less than the diameter of the interior of the said sleeve, and the length of the said end 22 from the conical shoulder 24 to the end of the plug 23 is substantially less than the length of the sleeve 17 from the conical bearing 20 thereon to the inner side of the end wall 18 of the sleeve.

To assemble the tone arm and the gooseneck it is merely necessary to insert the end 22 into the open end of the sleeve 17 and to then thread the screw 27 through the opening 19 in the closed end 18 of the sleeve 17, into the threaded hole 26 in the plug 23 and to draw the conical surface 25 on the gooseneck up into smooth bearing relation with the conical surface 20 of the open end of the sleeve 17. In this manner the two parts may be drawn so nicely together that there is no lost motion whatever between them. If, in the course of time, a slight wear should occur between the conical surfaces 20 and 25 and between the conical head 28 of the screw 27 and the conical hole 19 in the sleeve, it would be merely necessary to slightly turn the screw 27 sufficiently to draw the parts again into perfect bearing relations with respect to each other.

In this construction the bearing surfaces which are in engagement with each other are very small. There is very little frictional resistance to the free turning of the gooseneck within the sleeve 17, but at the same time there is no looseness or lost motion between the said parts, thereby obviating any noise, during the reproduction of sound due to the vibration of one part with respect to the other.

The larger end 22 of the gooseneck is provided with a transverse hole or opening 29 in substantial registration with the smaller end 16 of the tone arm and preferably elongated circumferentially, so that when the gooseneck 9 oscillates slightly within the sleeve 17, during the reproduction of sound from a record, the walls of the open-

ing 29 will not restrict or interfere with the free passage of the sound waves into the small end of the tone arm.

The diameter of the threaded portion of the screw 27 is slightly larger than the threaded opening 26 in the plug 23 of the gooseneck or sound box tube 9 and the screw 27 is preferably split diametrically and longitudinally, so that when the screw 27 is threaded into the opening 26 it will be compressed and will bind tightly in the opening and remain in fixed relation or stationary with respect to the plug when once adjusted.

In the assembled relation, the gooseneck or sound box tube turns or rotates within the sleeve on smooth narrow bearings provided by the said conical surfaces 20 and 25, and on the small pivot provided by the screw or stud 27. As shown in the drawings, the head 28 of the stud 27 is preferably conical and fits smoothly into the conical hole 19 in the closed end 18 of the sleeve 17, and therefore the gooseneck or sound box tube may be considered to be mounted on a pair of opposed narrow conical bearing surfaces on the tone arm, one (20) of relatively large diameter and the other (19) of relatively small diameter, said small surfaces providing the only surfaces of the sleeve or tone arm which engage or are in contact at all with the gooseneck or the parts mounted thereon or carried thereby.

Similarly the sound box tube or gooseneck 9 may be considered as provided with a pair of opposed conical bearing surfaces, one, the surface 25 on the shoulder 24 and the other, the conical head 28 of the screw 27, the screw threads on the screw 27 and in the plug 23 constituting means for drawing the said conical surfaces on the gooseneck into smooth bearing relation with the cooperating conical bearing surfaces on the sleeve or tone arm. When so viewed the sound box tube is mounted to freely rotate within the tone arm on two opposed conical bearings adjustable axially with respect to each other to provide for an accurate adjustment of the bearings and for taking up of wear therebetween.

By allowing ample clearance between the inside surface of the end 18 of the sleeve 17 and the surface of the adjacent end of the plug 23 and by making the diameter of the end of the gooseneck which is inserted into the sleeve substantially less than the diameter of the interior of the sleeve, slight variations in the length or diameter of the inserted end 22 of the gooseneck will not interfere with the proper mounting of the gooseneck within the sleeve, and therefore no particular accuracy is required in any of the over-all dimensions of the inserted end 22 of the gooseneck or sound box tube.

- While the larger end 22 of the gooseneck is shown and described as being preferably cylindrical it is to be understood that it may be of any other suitable shape, so long as it is out of contact with the inner surface of the sleeve, except at the narrow bearing surfaces above described, and is not of a shape to prevent the passage of the sound from the sound box to the tone arm proper.
- Having thus described my invention, what I claim and desire to protect by Letters Patent of the United States is:
1. In a sound conveying tube for talking machines, the combination of a tone arm, a sound box tube mounted to rotate within the end of said arm, said tone arm being provided with a conical bearing surface and said sound box tube being provided with a cooperating surface adapted to bear against said conical surface of said tone arm, and means for adjusting said surfaces with respect to each other and for taking up any looseness therebetween and for holding said surfaces in smooth bearing relation.
  2. In a sound conveying tube for talking machines the combination of a tone arm and a sound box tube, the end of said sound box tube being mounted to rotate within the end of said arm on two pairs of narrow opposed conical bearings one bearing of one of said pairs of bearings being adjustable toward and away from the other bearing of said pair of bearings.
  3. In a sound conveying tube for talking machines the combination of a tone arm provided with an opposed pair of narrow conical bearing surfaces, a sound box tube provided with a complementary pair of opposed narrow bearing surfaces, and means to draw and adjust the said opposed surfaces of said sound box tube toward each other, and each respectively against and into smooth bearing relation with one of said conical surfaces on said tone arm, and to securely hold said surfaces in such adjusted position.
  4. In a sound conveying tube for talking machines the combination of a tone arm terminating in a sleeve and interiorly beveled at one end to form a narrow conical bearing surface, a sound box tube having one end extending coaxially within said sleeve, said end being of a diameter substantially less than that of the interior of said sleeve, said sound box tube being provided with a shoulder having a conical surface, and means, arranged coaxially of said sleeve and said end of said sound box tube, secured to said end and turning therewith, to take up wear between and to hold the said conical surfaces on said sleeve and sound box tube in smooth bearing engagement and providing a pivot on which, and said conical surfaces, said sound box tube may rotate within said sleeve.
  5. In a sound conveying tube for talking machines the combination of a tone arm terminating in a sleeve and interiorly beveled at one end to form a narrow conical bearing surface, a sound box tube having one end extending coaxially within said sleeve, said end of said sound box tube being of a diameter substantially less than that of the interior of said sleeve, and means, arranged coaxially of said sleeve and said end of said sound box tube, secured to said end and turning therewith, to adjust said sound box tube longitudinally within said sleeve and to hold the said conical surfaces on said sleeve and sound box tube in smooth bearing engagement and providing a pivot on which, and said conical surfaces, said sound box tube may rotate within said sleeve.
  6. In a sound conveying tube for talking machines, the combination of a tone arm, terminating in a cylindrical sleeve open at one end and substantially closed at the other, but provided with a relatively small opening at the center of the closed end thereof, the open end of said sleeve being interiorly beveled to form a narrow conical bearing surface, a sound box tube having one end mounted within said sleeve with its inner end spaced from the closed end of said sleeve and of a diameter substantially less than that of the interior of said sleeve, and having a shoulder providing a narrow conical surface, and a screw passing through the said small opening in the end of said sleeve, tightly secured to and turning with said sound box tube, operative to adjust said tube longitudinally within said sleeve and to hold said conical surfaces together in smooth bearing relation, and providing a pivot on which, and said conical surfaces, said sound box tube rotates in said sleeve.
  7. In a sound conveying tube for talking machines, a tone arm terminating in a transverse cylindrical end open at one end and substantially closed at the other end but provided with a relatively small opening at the center of the closed end thereof, the open end of said sleeve being interiorly beveled to form a narrow conical bearing surface, a gooseneck having one end extending coaxially within said sleeve, said end of said gooseneck being of a diameter substantially less than that of the interior of said sleeve and of a length substantially less than that of said sleeve, said gooseneck being provided with a shoulder having a conical surface, and means arranged coaxially of said sleeve and said end of said gooseneck, passing through said small opening in the end of said sleeve, tightly secured to said gooseneck, turning therewith, operative to hold said conical surfaces on said sleeve and said gooseneck in smooth bearing engagement, and to take up any wear therebetween, and providing a pivot on which, and said coni-

cal surfaces, said gooseneck rotates within said sleeve.

8. In a sound conveying tube for talking machines, the combination of a tone arm and a sound box tube mounted to rotate within the end of said arm, said tone arm and said sound box tube being each provided with a conical bearing surface adapted to fit

one against the other, and means for adjusting said sound box tube longitudinally with-
in the end of said arm and for holding said conical surfaces in smooth bearing relation.

In witness whereof, I have hereunto set my hand this 21st day of June, 1921.

WILLIAM W. MOYER.
